UNITED STATES PATENT OFFICE

2,469,196

MAGNETO MAGNET

Harry Goldberg, Chicago, Ill., assignor, by mesne assignments, to Pioneer Gen-E-Motor Corporation, Chicago, Ill., a corporation of Delaware

Application January 4, 1946, Serial No. 639,128

2 Claims. (Cl. 171—209)

1

The invention relates to an improvement in magnetos and has for one purpose to provide an improved magneto structure.

Another purpose is to provide an improved permanent magnet for a magneto structure.

Another purpose is to provide an improved fly wheel structure with a permanent magnet forming an integral part of the wheel.

Other purposes will appear from time to time in the course of the specification and claims.

The invention is illustrated more or less diagrammatically in the accompanying drawings wherein:

Figure 1 is a vertical section, illustrating a fly wheel with its associated magneto weight.

Figure 2 is a section on the line 2—2 of Figure 1.

Figure 3 is a top view of the permanent magnet employed, and Figure 4 is a side elevation of the magnet shown in Figure 3.

Like parts are indicated by like symbols throughout the specification and drawings.

Referring to the drawings, 2 indicates any suitable base structure having a supporting edge 7 receiving the bottom wall 8 of any suitable engine block, not shown in detail and not of itself forming part of the present invention. 9 indicates a crank shaft mounted in any suitable bearings and including a crank portion 10. 11 illustrates a starting pulley. 12 is a fly wheel which may include a series of fan blades 13. The fly wheel 12 includes an inwardly extending rim 14 which partially surrounds a space about the crank shaft. 15 indicates a finned upper portion of the engine block. Since the details of the engine block and the engine do not of themselves form part of the present invention, they are not herein described or shown in detail.

In considering the magneto structure proper, I employ a permanent magnet 115 which may be cast in place in the flywheel 12, or may be received in any suitable recess in the wheel, as shown in Figure 2. It is to be understood that the flywheel 12 is of non-magnetic material. A variety of metals may be employed for the permanent magnet. I may, for example, employ an aluminum-nickel alloy. A suitable alloy is one known in the trade as Alnico No. 5. The permanent magnet is shown as having two end or pole portions 115a and 115b separated by a depression 115c. When the parts are cast integrally together, as shown 50

in Figure 2, the magnet may be firmly held in position by the transversely extending integral portion 12a of the fly wheel 12. However, any other suitable means may be employed for holding the magnet in permanent position.

Housed within the fly wheel extension 14 is the E shaped magneto core 116 with any suitable coil 117 surrounding the intermediate arm of the E shaped core. The coil is mounted on any suitable frame or support 118 which is mounted on hub extensions 119 of the plate 24.

The crank shaft 9 is provided with a raised cam portion 120 which may be part of the crank shaft or a separate added part. The object is to reduce wear on the plunger 121, permitting the plunger to run free of the crank shaft for approximately 330 degrees, thus reducing wear. The breaker plunger 121 is mounted on or controls the breaker lever 123 which carries the point 124 opposed to the opposite contact or point 125. 126 is any suitable condenser. It is advantageous to tilt the fixed magneto structure shown in Figure 2, in relation to the horizontal, to an angle which may be as high as 45 degrees. This prevents oil leakage collecting on the breaker points and resultant contamination.

For the permanent magnet I may use an alloy of aluminum, nickel and cobalt, which use gives us, for the amount of material, great magnetic strength, and consequently improvement in magneto performance. However, other metals may be employed. The employment of metal of the general characteristic of the above alloy permits the use of a smaller permanent magnet or insert than has in the past been possible. Note that the permanent magnet extends about an arc of the order of about 15 degrees, more or less, and preferably substantially less than 45 degrees. The number of lines of flux has been increased and the result is a hotter spark, making starting much easier than in previously conventional magneto fly wheel designs.

It will be realized that, whereas, I have described and illustrated a practical and operative device, nevertheless many changes may be made in the size, shape, number and disposition of parts without departing from the spirit of the invention. I therefore wish my description and drawings to be taken as in a broad sense illustrative

or diagrammatic, rather than as limiting me to my precise showing.

I claim:

1. In combination, a fly wheel of non-magnetic cast metal having a laterally projecting flange, a one piece bar magnet embedded in cast relationship within the inner face of the flange, there being two cylindrical pole faces on one side of the bar magnet one adjacent each end thereof, said faces being exposed in the inner periphery of the flange and of substantially greater area than the cross-sectional area of said magnet intermediate its ends, a bridge cast integral with the flange extending across the body of the magnet between and separating the pole faces, the width of the bridge being substantially greater than its radial thickness.

2. In combination, a fly wheel of non-magnetic cast metal having a laterally projecting flange, a one piece bar magnet embedded in cast relationship within the inner face of the flange, there being two cylindrical pole faces on one side of the bar magnet one adjacent each end thereof, said faces being exposed in the inner periphery of the flange and of substantially greater area than the cross-sectional area of said magnet intermediate its ends, a bridge cast integral with the flange extending across the body of the magnet between and separating the pole faces, the width

of the bridge being substantially greater than its radial thickness, the inner peripheral surfaces of the bridge and the flange adjacent the magnet being concentric with and aligned with the pole faces.

HARRY GOLDBERG.
